UNITED STATES PATENT OFFICE.

JULIUS F. YOUNG, OF OWATONNA, MINNESOTA.

FLUSHING DEVICE FOR WATER-CLOSET TANKS.

936,396.

Specification of Letters Patent.

Patented Oct. 12, 1909.

Application filed September 22, 1908. Serial No. 454,141.

To all whom it may concern:

Be it known that I, JULIUS F. YOUNG, a citizen of the United States, and a resident of Owatonna, in the county of Steele and State of Minnesota, have invented a new and Improved Flushing Device for Water-Closet Tanks, of which the following is a full, clear, and exact description.

The purpose of the invention is to provide 10 an independent automatic locking device, adapted for use in connection with the customary float locking supply valve, and which, although it may be used for other purposes, is especially designed to be employed in water-closet tanks.

This improved apparatus provides a simple and economic means for double locking and compressing the packing of the supply valve, whereby to cause it to bear against 20 the collar and hold it securely locked, so that even if the flushing valve were to leak and discharge all the water in the tank, it would not supply more water, unless it should be desired to flush the closet by intentional operation of the flushing lever.

A further feature of the invention consists in the employment of an auxiliary weighted locking lever that will cause the customary ball float supply valve to instantaneously 30 close.

The invention consists in the novel construction and combination of the several parts, as will be hereinafter particularly described and pointed out in the claims.

Reference is to be had to the accompanying drawings forming a part of this specification, in which similar characters of reference indicate corresponding parts in all the views.

Figure 1 is a vertical section through the tank, illustrating the flushing device in side elevation and in inactive position; Fig. 2 is a plan view of the tank and flushing device; Fig. 3 is an enlarged sectional view on the line 3—3 of Fig. 2, of the controlling means for the flushing or discharge valve, the float rod being broken away; Fig. 4 is a side elevation of the parts shown in Fig. 3, parts being broken away; Fig. 5 is an exterior view of the standard or sustaining mechanism for the controlling lever, the view being taken in the direction of the arrow 5 in Fig. 3; Fig. 6 is an exterior view of the parts shown in Fig. 5, the view being taken in the direction of the arrow 6 in Fig. 3; Fig. 7 is a detail vertical section taken practically on

the line 7—7 of Fig. 3; and Fig. 8 is a detail section taken substantially on the line 8—8 of Fig. 3.

In connection with my improved device, 60 I employ the customary discharge valve A, for flushing purposes, having a proper seat A' and a connection A², with the closet bowl or other article to be flushed. The valve A is operated by a strap or similar connection 65 A⁴, with a lever A³ of any desired type, fulcrumed upon a bracket 10 secured to the upper edge of the tank A⁶, and operated by an attached chain or cord A⁵, or the equivalent of the same.

At the bottom of the tank A⁶, suitably removed from the flushing valve A, a casing 12 for an inlet or supply valve, is located, having a discharge nozzle 13 within the tank, and suitable connection 14, with a 75 source of water supply. The nozzle 13 is provided with a flange 13^a which abuts against the side of the tank and prevents disarrangement when coupling the valve 12 or uncoupling the tank and the connection 14. 80

The valve casing 12 is provided with friction rollers 15 extending to the interior of the casing, as shown in Fig. 3, being adapted for engagement with a valve 16, slideable in the casing and provided with an upper 85 chamber 17, and preferably with a roller bearing pivot pin 18, that crosses the said chamber; and normally the valve 16 rests upon a suitable seat 19 from which it may be raised or forced to seat itself, through the 90 medium of a float having connections to be hereinafter set forth. The valve casing 12 is provided with opposing upwardly extending members 20 and 20^a, that act as standards.

The main stem 21 of an operating arm B is located and pivoted between the standards 20 and 20^a, which stem is bifurcated at its upper end above said standards. The members 22 and 23 formed by said bifurcation, 100 are carried upwardly, the member 22 being preferably the shorter one and having more of an abrupt upward inclination than the member 23, as is shown in Fig. 3.

The member 23 carries any desired number of removable weights 24, usually located upon a threaded rod 25, and held in place by a thumb nut 26 or the like; the number of weights employed being dependent on the different pressures of city water plants.

The shorter member 22 of the operating arm B, is provided with a grooved pulley

27, that engages the under face or edge of the lever A³ at the rear of its fulcrum, so that said arm B is swung out to the position shown in dotted lines in Fig. 3, when the 5 said lever A³ is drawn downward to open the flushing valve A to permit of the inlet-valve 16 being opened.

The pulley 27 is rendered adjustable by being mounted upon a forked slide 28 mounted on said member 22, as shown in Fig. 7, and has a slot 29 therein, and a set screw 30 is passed through the slot.

The stem 21 of the arm B is pivoted on a pin 31. In connection with the main stem 15 21 of the operating arm B, a valve-controlling member 32 is provided, terminating at its lower end in a head 33, that extends beneath the main stem 21, having a rounded bottom face and a correspondingly curved 20 nose 34 extending therefrom, as is illustrated in Fig. 3. The head 33 normally has such bearing upon a roller 35 at the upper end of the inlet or supply valve 16, as to keep the valve closed, as is also shown in Fig. 3. 25 The valve-controlling member 32 of the operating arm B is vertically adjustable, so as to exert greater or less pressure upon the said inlet valve, by producing slots 36 in the controlling member 32 and passing set 30 screws 37 through said slots into the stem 21, and also by passing an adjusting screw 38 through the bifurcated upper portion of the operating arm to a bearing upon the valve controlling member 32 of said arm, as 35 is shown in Figs. 3 and 7.

The roller bearing 18 carried by the inlet valve 16, is partially surrounded by a fork 39, said fork having ample play relatively to the pin, as is shown in Fig. 3. The shank 40 or arm of the fork 39 extends freely out through an opening in the side of the valve casing 12, as is shown in Fig. 8, and has interlocking yet adjustable connection with the shank of a socket 40, that carries the 45 stem 41 of the float 42. The pivotal and adjustable connection between the two said parts 39 and 40, as is also best shown in Fig. 8, is effected by a suitable pivot pin 43 passed through the parts 39 and 40, and through 50 ears 44 at the sides of the opening in the casing, through which parts 39 and 40 the pin loosely extends, being secured to one of said ears, as is also shown in Fig. 8. The member 39 adjacent to its pivotal connection 55 with the member 40, and at a point adjacent to the aforesaid pivot 43, is formed into a flat extension 45 having a segmental slot 46 produced therein, as is illustrated in Fig. 8; and an adjusting screw 47 is passed through 60 said section 45 at the slot 46, and is threaded into the socket member 40, as is also shown in Fig. 8. Thus in the construction of said float connection, it will be observed that the parts or members 39 and 40 can be adjusted 65 and held in adjustment to admit of a greater

or less amount of water being discharged from the tank, due to the inclination of the stem of the float, and that the said float in rising and in dropping, will operate the inlet valve and open the same, when the tank is 70 comparatively empty, and will close the valve after the tank has received its proper supply of water. In addition to the aforesaid functions of the float 42, the said cock so operates that should a leak occur at the 75 flushing valve A, or at other parts of the tank, only that amount of water in the tank can escape, and no water can be admitted to the tank until the lever A³ is operated for another flushing operation. This action is 80 accomplished as follows: A locking arm 48 is carried upward from the part 45 of the float member 39, having a bifurcated upper end 49 that carries a roller 50, which roller, when the float rises and the inlet valve 16 is 85 closed, engages the inner face of a tooth 51 at the under face of a latch lever 52 pivoted to the standard 20, for example, by a suitable pivot pin 53, and at the inner side face of this latch lever a substantially triangular 90 lug 54 is formed, see Figs. 3 and 6, and a corresponding lug 55 is formed upon the lower portion of the main stem 21 of the operating lever B, in such manner that when the roller-bearing upper end of the operating arm or lever is carried downward and its lower end is swung out from between the standards 20 and 20^a, the latch-lever 52 having been raised by the engagement of the roller 50 with the tooth 51 on said latch 100 lever, the lug 55 on the operating arm will so engage with the lug 54 on the latch-lever 52 as to hold the operating lever in its tripped position, as shown in dotted lines in Fig. 3. At this time the flushing valve A is 105 opened and float 42 gradually settles to the bottom of the tank A⁶, and as the locking arm 48 is thrown back it disengages the latch lever 52, allowing the lug 54 to engage the lug 55 on the operating arm B whenever 110 the flushing lever A⁸ is pulled.

When the float 42 reaches the lowest position, or approximately so, the valve 16 is opened and water is admitted to the tank, the flushing valve A closing itself by suction 115 in the usual manner. During the discharge of the water, the stem attachment for the float 42 retains the inlet valve 16 in closed position, opening it as stated when the float is near the bottom of the tank. As the float 120 42 rises, a cam 56, adjustable by means of a set screw 56^a carried by the locking arm 48, presses down the yoke section 58 of a lock lever C by passing through a slot 59 in said yoke section 58. The lock lever C 125 is provided with a weight 60 which assists in the operation. A suitable stop 61 is provided for the latch lever 52, as is shown in Fig. 4, and a like stop may be provided for the lock lever C. 130

By the adjustment of the cam 56 through the set screw 56^a, the time of closing the inlet valve may be regulated as desired. The yoke section 58 of the lock lever C is pivoted to the standards 20 and 20^a in such manner that when the operating arm B is carried to the angular position shown in dotted lines in Fig. 3 and in full lines in Fig. 4, and the lugs 54 and 55 are in locking engagement, the operating arm B cannot return to its normal position until the yoke section 58 of the lock lever C is depressed from the position shown in Fig. 4 to the position shown in Fig. 3. This position is assumed at or about the time the float 42 reaches its upper position. The yoke section 58 of the lock lever C acts as an additional locking means to prevent the operating arm B from returning to normal position before the proper time.

It is evident that when the parts are in the position just stated, should there be any leakage at the flushing valve, or anywhere else in the tank, only that amount of water in the tank can escape, and that no more can enter until the flushing lever A³ is operated.

Having thus described my invention, I claim as new and desire to secure by Letters Patent:

30 1. In a flushing apparatus, the combination with a flushing valve, and means for operating the same, of an inlet valve, a float for operating the inlet valve, and a locking device for the inlet valve, said locking device being set into operation by the means for operating the flushing valve and controlled by the float.

2. In a flushing apparatus, the combination with a flushing valve and means for operating the same, of a supply valve, an operating arm adapted for locking engagement with and release from the supply valve, means whereby the operating arm is controlled by the operating medium for the flushing valve, means for holding the said operating arm in locking or releasing position, and a float mechanism for controlling the return movements of said operating arm.

3. In a flushing mechanism, a flushing valve, a supply valve, an arm controlling the supply valve, means for operating said arm concerted with the flushing means, a locking device for holding said arm in position, a float, and means controlled by the float for restoring the arm to locking engagement with the supply valve.

4. In a flushing mechanism, a flushing valve, a supply valve, means for releasing the supply valve at the opening of the flushing valve, means for automatically closing the supply valve at a predetermined time, and means for holding the supply valve closed during a period of leakage.

5. In a flushing mechanism for water-closet tanks and the like, in combination

with the flushing valve and means for operating it, a supply valve, a pivoted operating arm for the supply valve, operated directly by the operating means for the flushing valve, a float directly in operative engagement with the supply valve to raise and lower it, and locking and releasing means controlled by the float and controlling the return movement of the said operating arm.

6. In a flushing mechanism for water-closet tanks and the like, in combination with the flushing valve and means for operating it, a supply valve, a rocking arm adjustable to and from the supply valve, devices for operating said arm by the movement of the operating means for the flushing valve, a float, locking means controlled by the float for temporarily holding the rocking arm inactive, and means coacting with the locking means for releasing the rocking arm at the upward movement of the float.

7. In a flushing mechanism for water-closet tanks and the like, the combination with the flushing valve and means for operating it, of a supply or inlet valve, a weighted rocking arm provided with a section adjustable to and from the supply or inlet valve, which arm is operated from the inlet valve by the operative means for the flushing valve, a float operatively connected with the inlet valve, locking means for holding the rocking arm in the releasing position, and means operated by the float for releasing said locking means at a predetermined time.

8. In a flushing mechanism for water-closet tanks and the like, the combination with a flushing valve and means for operating it, of an inlet valve, an adjustable float operatively connected with the said inlet valve, a weighted operating arm provided with a member adjustable to and from the inlet valve, a pivotal support for said rocking arm, a latch carried by said support, a weighted lock lever pivoted upon said support, an arm carried by the float mechanism for engagement with the latch, and a cam carried by the float arm, operating upon the lock lever to permit said lever to remain in the path of the operating arm or remove it therefrom, according to the position of the float, the said locking means remaining active at all times until the flushing valve is opened.

9. In a flushing apparatus, the combination with a flushing valve, and means for operating it, of an inlet valve, a float for operating said valve, a swinging arm operated by the means for operating the flushing valve and serving to keep the inlet valve closed, and means controlled by the float for locking the swinging arm in position to permit the inlet valve to open.

10. In a flushing apparatus, the combina-

tion with a flushing valve, and means for operating said valve, of an inlet valve, a float for operating the said valve, a pivoted and counterbalanced arm for holding the valve closed, said arm being operated by the means for operating the flushing valve to move it into inoperative position, means controlled by the float for locking the pivoted arm in inoperative position and releasing the same.

11. In a flushing apparatus, the combination with a flushing valve, and a pivoted lever for operating said valve, of a sliding inlet valve, a float for operating said valve, a pivoted arm having at one end a member

for holding the inlet valve closed and at its other end two members, one of which is weighted and the other extends into the path of the flushing valve operating lever, a latch for locking the pivoted arm in inoperative position, and means controlled by the float for operating the latch.

In testimony whereof I have signed my name to this specification in the presence of two subscribing witnesses.
